W. J. HOTCHKISS.
RAIL FASTENER.
APPLICATION FILED JUNE 7, 1916.

Patented Sept. 26, 1916.

UNITED STATES PATENT OFFICE.

WALLACE J. HOTCHKISS, OF ALPENA, SOUTH DAKOTA

RAIL-FASTENER.

1,199,465.

Specification of Letters Patent. Patented Sept. 26, 1916.

Application filed June 7, 1916. Serial No. 102,286.

To all whom it may concern:

Be it known that I, WALLACE J. HOTCHKISS, a citizen of the United States, residing at Alpna, in the county of Jerauld and State of South Dakota, have invented certain new and useful Improvements in Rail-Fasteners, of which the following is a specification, reference being had to the accompanying drawings.

10 This invention relates to an improved rail fastener and has for its primary object to provide a very simple and effective device to prevent the spreading of the rails and also obviate rotting or decaying of the tie beneath the rail.

It is an additional object of the invention to provide a device for the above purpose embodying chair plates adapted to be inserted from opposite sides of the tie beneath the rail, and adjustable clamping means mounted upon each of the chair plates for engagement with one edge of the rail base.

It is an additional object of the invention to provide improved means for securely spiking the chair plates to the tie to prevent their movement with respect to each other or with relation to the tie.

With the above and other objects in view, my invention consists in the novel features of construction, combination, and arrangement of parts to be hereinafter more fully described, claimed, and illustrated in the accompanying drawings, in which,

25 Figure 1 is a perspective view illustrating the application of my improved rail fastener in practical use; Fig. 2 is a transverse section showing the mounting and construction of the clamping devices; Fig. 3 is a section taken on the line 3—3 of Fig. 2; Fig. 4 is a detail perspective view of one of the clamping devices; and Fig. 5 is a detail perspective view of one of the spikes.

Referring in detail to the drawing, 5 designates the tie plates, each of which includes an elongated body portion 6 having a relatively narrow lateral extension 7 upon one end. The tie plate at the juncture of the extension with the body 6 is formed with a vertical flange 8 which projects beyond the opposite ends of the body portion 6 of the tie plate and is adapted for engagement against one side of the tie, indicated at T. Upon one of the longitudinal edges of the lateral extension 7 on each tie plate, an upwardly and inwardly extending clamping

lug 9 is formed. Adjacent to this lug, the under side of the extension 7 is formed with an enlargement 10, having an opening 11 therethrough disposed transversely of the extension 7 on the tie plate.

In arranging the tie plates in position upon the tie, the same are disposed with their body portions 6 in superposed relation upon the upper surface of the tie and the vertical flanges 8 engaged closely against the opposite side faces of the tie. Coinciding spike receiving openings are formed in the ends of the body portions 6 of the tie plates to receive the spikes 12, driven into the tie. Similar spikes 13 are also driven horizontally into the body of the tie through openings in the ends of the flanges 8. These spikes, as clearly shown in detail in Fig. 5 are each provided with a rectangular enlargement 14 on one side of its shank portion beneath the head of the spike, said enlargement being beveled or tapered at its lower end and merging into the side face of the shank, as at 15. These shank enlargements engage through the openings in the body portion 6 and the flanges 8 of the tie plates and also enter the tie whereby turning movement of the spikes is effectually prevented, and the tie plates are also securely fixed in place against relative movement.

It will be observed that the clamping tongues 9 are formed upon the relatively opposite longitudinal edges of the extensions 7 of the respective tie plates. Adjacent to the opposite edge of each of these extensions and upon the under side thereof, a guide strip or loop 16 is formed to receive a flat rectangular clamping plate 17. The outer end of each of the clamping plates is upwardly and evenly curved to form the clamping tongues 18 which are opposed to the tongues 9 and are adapted for clamping engagement over the opposite edge of the rail base. The clamping plates 17 are each formed upon one end of a bolt 19 which is movable through the opening 11 provided in the enlargement 10 formed upon the extension 7 of the tie plate, which extends longitudinally beneath the base of the rail. The outer end of each of these bolts is threaded to receive one or more clamping nuts 20. Suitable washers 21 are preferably interposed between the nuts and the outer ends 110 of the enlargements 10.

From the above description it will be seen

that after the rail has been arranged upon the tie plates, which have previously been secured to the tie in the manner stated, the clamping members are adjusted to draw the 5 tongues 18 inwardly into tight clamping engagement with the edges of the rail base, and the rail secured between said tongues and the opposed fixed clamping tongues 9. In this manner the rail is securely held in place 10 and spreading thereof is effectually prevented. The metal tie plates extending beyond the opposite sides of the rail also prevent the collection of rain water beneath the rails and thus obviate the rotting or decay 15 of the tie.

From the foregoing description, taken in connection with the accompanying drawings, the construction, manner of operation and several advantages of my invention will 20 be clearly and fully understood. By means of the device, it will be apparent that the rail can be easily, quickly and securely fastened in place upon the tie or readily removed therefrom, when necessary.—

25 The device consists of few parts and it is apparent that the invention will be very durable in practical use and may also be produced at relatively small manufacturing cost.

30 While I have shown and described the preferred construction and arrangement of the several features, it is to be understood that the device is susceptible of considerable modification thereof and I therefore reserve 35 the privilege of adopting all such legitimate changes as may be fairly embodied within the spirit and scope of the invention, as claimed.

Having thus described this invention, what 40 I claim is:—

1. In a rail fastener, a tie plate provided with a lateral extension to project longitudinally beneath the rail at one side of the tie, said extension having a clamping tongue 45 formed on one edge thereof for engagement over one edge of the rail base, a transversely adjustable bolt mounted upon the under side of said extension, a guide strap on the

under side of said extension, and a clamping plate projecting from the end of said bolt 50 movable between the guide strap and the extension and having an inwardly and upwardly projecting tongue formed on one end for clamping engagement with the opposite edge of the rail base. 55

2. In a rail fastener, a tie plate provided with a lateral extension to project longitudinally beneath the rail at one side of the tie, said extension having a clamping tongue 60 formed on one edge thereof for engagement over one edge of the rail base, said extension being formed with an enlargement on its under side adjacent the tongue, and formed with an opening therein, a bolt movable through said opening, a plate projecting longitudinally on one end of the bolt, guide means for said plate on the inner end of the extension, said plate having an upwardly and inwardly projecting tongue formed on its end for engagement over the 70 opposite edge of the rail base, and a clamping nut threaded upon the outer end of said bolt. 65

3. In a rail fastener, complementary tie plates, each having a body portion, a laterally projecting extension, and a vertical flange, said body portions being adapted for arrangement in superposed relation upon the upper surface of the tie, and said flanges engaging upon the opposite side faces of the 80 tie, spikes to secure the body portions and the flanges of the tie plate to the tie, each of said extensions being provided with an inwardly projecting tongue on one of its longitudinal edges for engagement over one 85 edge of the rail base, and a transversely adjustable clamping member mounted upon the under side of the extension for engagement with the opposite edge of the rail base. 75

In testimony whereof I hereunto affix my 90 signature in the presence of two witnesses.

WALLACE J. HOTCHKISS.
